UNITED STATES PATENT OFFICE.

JACOB F. PRATT AND WELLINGTON CHASE, OF COLDWATER, MICHIGAN.

CHILD'S SLED.

SPECIFICATION forming part of Letters Patent No. 380,693, dated April 10, 1888.

Application filed January 4, 1888. Serial No. 259,766. (No model.)

To all whom it may concern:

Be it known that we, JACOB F. PRATT and WELLINGTON CHASE, citizens of the United States, residing at Coldwater, in the county of Branch and State of Michigan, have invented certain new and useful Improvements in Reversible Handles for Children's Sleds, &c.; and we do hereby declare the following to be a full, clear, and exact description of the invention, 10 such as will enable others skilled in the art to which it appertains to make and use the same.

Our invention relates in general to that class of devices by which the handles ordinarily applied for the pushing of children's sleds, carriages, or other vehicles can be unfastened 15 from their normal position at the rear of the vehicle and reversed or applied to the front thereof for enabling the pulling of the vehicle as opposed to the pushing of the same; and it 20 relates in particular to that class of devices in which the attachable and detachable connection of the handles to the front ends of such vehicles is effected by means of hooks applied to the side bars of said handles and adapted to 25 be engaged with eyebolts or similar retaining devices applied at said front ends, and in which the connection of said handles to and from the rear ends of said vehicle is effected by means of locking or clamping devices.

30 The object of our invention is the provision of improved means for securely locking or clamping the handles to the rear ends of children's sleds or carriages when applied thereto, and for securely holding said handles at the front 35 ends thereof by side bars having hooks at their ends, the devices whereby this object is accomplished being simple in construction, easily understood, readily and quickly operated for attaching and detaching the handle, and not 40 liable to permit the same to become accidentally detached from the position in which it is placed; and our invention consists in the construction and arrangement or combination of parts hereinafter disclosed in the description, 45 drawings, and claims.

In the accompanying drawings, forming part 50 of this specification, wherein the same reference-letters indicate the same parts, and wherein in a child's sled is shown as an instance of the embodiment of our invention, Figure 1 represents a perspective view of our invention applied to the rear end of a sled; Fig. 2, a side

elevation of a sled with the handle attached to the front end thereof; Fig. 3, an enlarged elevation of the rear end of a sled, and also of the 55 lower ends of the side bars of the handle when drawn together or in position for attachment; and Fig. 4, an enlarged elevation, partly broken and in section, showing in detail one of the lever clutches and its plate for locking 60 the handle in fixed and removable position against the rear end of the sled.

In the drawings, A represents the body of a sled or carriage provided with eyebolts B B upon each side and near the lower edge of its 65 rear end, and with socket or recessed plates C near the sides and upper edge of said rear end, to which the side bars of the handle are secured.

D represents the handle, which consists of 70 the cross-bar D' at its upper end and of the side bars, D² D², and is provided with a laterally-adjustable bracket or brace, D³, which connects the lower ends of said side bars, whereby they may be drawn together or spread 75 apart for respectively disengaging the handle from or attaching it to either end of the sled or carriage.

The adjustable bracket or brace D³ is made in two sections or parts, d' d², which are held 80 by screws d³ d³ to the inner surfaces of the side bars, D² D², and each of said sections or parts has a hook, d, at its lower end for engaging with one of the eyebolts B B near the lower edge of the rear end of the sled.

A clamping-bolt, E, is screwed into a threaded hole in the section or part d', passes through a long slot, d', in the other section or part, d², of the bracket or brace D³, and serves when fastened to securely hold the side bars of the 90 handle and said sections or parts in fixed position when engaged with the eyebolts B B upon the rear end of the sled or carriage-body; also, this construction will operate to hold the handle in a similar manner in engagement with 95 the eyebolts B' B' at the front end of the sled or carriage.

When the sections of the adjustable bracket or brace D³ are unclamped or unlocked by loosening the clamping-bolt E, the hooks d d 100 at the lower end of the side bars of the handle may be easily withdrawn from the eyebolts by pressing said side pieces of the handle toward each other, and may be held in this contracted

position by said clamping-bolt until the handle is again placed in position to be secured upon either end of the body of the sled or carriage.

5 The handle D is locked securely in fixed position against the rear end of the body A of the sled by means of lever-clutches F F, pivoted to the outer surfaces of the side bars, D² D², of the handle, and engaging with the recessed or socket plates C C, secured by screws c' c' to the rear end of the sled. These recessed or socket plates have rectangular slots c² c³, located one above the other and passing through said plates, with which the cam-shaped hooks f f of the lever-clutches engage, to be held securely therein. By moving the lever-clutches F F rearward their cam-shaped hooks f f are first passed forward through the lower slots, c² c³, and then up through the upper slots, c³ c³, 20 of the socket-plates C C, and thus the handle is drawn forward and clamped or locked closely and securely against the rear end of the sled or carriage.

25 The clamping or screw bolt E has widely spreading wings e e, and the lever-clutches F F have handle-extensions f' f', of sufficient length to enable them to be easily operated without removing gloves from the hands.

30 With the parts constructed as described, the handle D is adapted to be quickly moved from the front to the rear of the sled or carriage and securely clamped in either position, thus providing a perfectly safe and reversible handle; also, it will be readily seen that handles thus 35 securely attached will avoid the accidents which sometimes occur to children when their attendants lose control of the sleds or carriages upon the accidental detachment of the handles therefrom.

40 The handle may be made, if preferred, of a single continuous piece bent at the upper end or middle, and other minor changes in the construction and arrangement of the parts of our invention may be made without departing 45 from the nature or principle thereof. We are aware, however, that reversible handles for children's sleds or carriages are not broadly new; but we know of none which admit of easy and quick detachment from one end and 50 attachment to the other end of the body of a vehicle, which can be securely clamped or locked in either position, and which will not admit of accidental detachment.

Having thus fully described our invention, 55 what we claim as new is—

1. The combination, with a child's vehicle provided with attaching devices at its front and rear ends, of a handle and a laterally-adjustable clamping device formed in two sections and provided at their inner ends with a 60 long slot and a clamping-screw, substantially as and for the purpose described.

2. The combination of the body A of a child's vehicle, provided with eyebolts B B, with a handle, D, provided with a laterally-adjustable bracket or brace, D³, arranged between the side bars, D² D², of said handle, whereby said side bars may be spread apart or drawn together, substantially as and for the purpose described. 70

3. The combination of the body A of a child's vehicle, provided with eyebolts B B, with a handle, D, provided with a laterally-adjustable bracket or brace, D³, consisting of two sections or parts, d' d', having hooks d d, 75 a slot, d⁴, and a clamping or screw bolt, E, substantially as and for the purpose described.

4. The combination, with the rear end of a child's vehicle provided with recessed or socket plates, of a handle having side bars, 80 and lever-clamps pivoted to said side bars and provided with cam-shaped hooks, substantially as and for the purpose described.

5. The combination, with the rear end of a child's sled or carriage, of a handle pivotally supported thereon near its lower edge, recessed or socket plates arranged near the upper edge and sides thereof, the handle, and the pivoted lever-clutches having cam-shaped hooks and secured to the side bars of said handle for engaging with the recess of said plates, substantially as and for the purpose described. 85

6. The combination, with the rear end of a child's sled or carriage, of a handle pivotally supported thereon near its lower edge, recessed or socket plates arranged near the upper edge and sides thereof, the handle, the pivoted lever-clutches having cam-shaped hooks and secured to the outer surfaces of the side bars of said handle, and a laterally-adjustable bracket or brace arranged between said side bars, substantially as and for the purpose described. 90

In testimony whereof we affix our signatures in presence of two witnesses.

JACOB F. PRATT.
WELLINGTON CHASE.
